H. T. BUSSMANN

ELECTRIC FUSE

Filed May 7, 1919

INVENTOR

HENRY T. BUSSMANN,

by *J. G. Melius*. ATTORNEY.

UNITED STATES PATENT OFFICE.

HENRY T. BUSSMANN, OF ST. LOUIS, MISSOURI.

ELECTRIC FUSE.

Application filed May 7, 1919. Serial No. 295,371.

To all whom it may concern:

Be it known that I, HENRY T. BUSSMANN, a citizen of the United States, residing at St. Louis, Missouri, have invented a certain new and useful Electric Fuse, of which the following is a full, clear, and exact description, such as will enable others skilled in the art to make and use the same.

My invention relates to electric fuses and refers particularly to that type of fuses known as the refillable cartridge fuse; yet I do not limit my invention wholly to this type as certain of my improvements are likewise desirable in other types of fuses.

15 The object of my invention is to provide a fuse that is simple in construction, can be manufactured at a low cost and can be easily renewed.

In the drawings, Fig. 1 shows my fuse, 20 a portion being broken out to illustrate the interior thereof. Fig. 2 is a side view of the member attached to the end of the casing. Fig. 3 is an inside end view of this member, indicating by dotted lines the terminal fitted therein. Fig. 4 is an outside 25 end view of this member. Fig. 5 is a view similar to Fig. 1 with the fuse at an angle of ninety degrees from the position there shown. Fig. 6 is a view of the fuse link 30 shown in Fig. 1.

In the drawings, 6 is a casing. 7 is a member, preferably of metal, attached to the casing in any suitable manner, as, for example, rivets 8. 9 is a shoulder on the 35 member, shaped to fit snugly into cap 10.

It is well known that fiber, which is principally used as a casing, will wear very easily, and that it will shrink and swell. Where the cap or closure sets directly on such fiber casing, there is no assurance that a tight fit will be obtained and that such tight fit will be maintained. The shrinking of the fiber permits the escape of gas and flame on the blowing of the fuse. 40 The swelling of the fiber prevents the removal of the cap. For this reason I arrange the outside portion of element 7, so that the cap 10 will fit closely over it, thereby preventing the escape of flame and gases 45 on the blowing of the fuse and at the same time permitting easy removal of the cap.

The member 7 is provided with two or more projections 11, as shown in Figs. 2 and 3, that extend within the casing. The space 50 between these projections is of such a dimension as to fit the terminal 12 closely and

still permit ready removal and insertion of the terminal so that the terminal is held against rotational and sidewise movement. One of these members 7 is placed on each 60 end of the casing with the spaces between the projections properly positioned, so that the terminals are held in the same plane.

It will be readily understood by those versed in the art that the arrangement can 65 be readily used in fuses having other methods for holding the closure in place than that here shown.

To terminals 12 are detachably connected fuse strip 13, by any means, for example, bolts 14. 15 shows projections on the fuse link, preferably stamped out so as to hold the strip in predetermined alignment. This prevents the link from being pulled out of line with the fuse strip when the bolts 14 75 are pulled up tight.

Through holes 16 in the member 7 and through opening 17 in terminals 12, is passed a bolt 18, which is held in place by the nut 19, or any other means, such as threads 80 in the member. It is obvious that I may use such holding means on a member attached to the outside of the casing.

It will be noted that I have shown the opening 17 in the terminal of a length 85 greater than the diameter of the bolt that passes therethrough. This is done to overcome the variation in length of the assembled terminals and fuse link, which variation is due to the clearance necessary in the 90 bolt holes in the copper terminals and fuse link, and the variations in the length of the structure, comprising the casing and closures.

In manufacturing my fuse, I may make 95 either the holes 16 in the member 7, or the opening 17 in terminal 12, or all of them, of a length greater than the diameter of the bolt used. This arrangement may be provided on the part or parts at one end of the 100 fuse only, but to preserve uniformity of parts I prefer that both ends of the fuse be alike. Where the variations referred to are eliminated, or where other means for taking care of these variations are provided, I 105 may make these holes only long enough to pass the bolt 18 therethrough.

I claim as my invention:

1. In a refillable fuse, a casing, a member extending within the casing and positioned therein, a terminal having an opening 110 therein extending within the member, a

- cap and a unitary means for detachably positioning the cap and the terminal.
2. In a refillable fuse, a casing, a ring-shaped member, means for attaching the member to the casing, a terminal extending within the casing, a cap, detachable holding means connecting the cap to the member and positioned in an aperture in the terminal, said aperture being of a size as to allow a certain limited movement of the terminal relative to the detachable holding means.
3. In a refillable fuse, the combination of a casing, a ring shaped member, a terminal extending into said member, a cap, detachable holding means extending through spaces in cap, element and terminal, which spaces in said terminal have a substantial clearance to allow a certain limited movement of the terminal relative to the holding means.
4. In a refillable fuse, a casing, a ring shaped member fastened to the casing, a cap, a terminal extending within the casing, detachable fastening means extending through an opening in the member and engaging the terminal, the opening in the member having a substantial clearance to allow a certain limited movement of the terminal relative to the detachable fastening means.
5. In a refillable fuse, a casing, a cap, a

terminal, a ring shaped member, means for attaching the ring shaped member to the casing, a detachable cap-fastening means extending through the ring shaped member and engaging a recess of substantial clearance in the terminal. 35

6. In a fuse, a casing, a closure, a terminal, a member having a plurality of projections within the casing, said projections being adapted to hold the terminal against rotational movement and a portion thereof outside the casing for holding the closure. 40

7. In a refillable fuse, a casing, a member having projections extending within the casing, a flat blade terminal adapted to be passed through the member; the projections on the member providing oppositely disposed recesses to position the terminal against rotational and sidewise movement. 45

8. In a refillable fuse, a casing, a cap, a ring shaped member attached to the casing, holding means extending transversely through the portion of the member beyond the casing for detachably holding the cap. 50

9. In a refillable fuse, a casing, a closure, a structure comprising terminals and a fuse link and means on the fuse link for engaging the sides of the terminals to establish and maintain the structure in alignment. 60

HENRY T. BUSSMANN.
